ABSTRACT: As an abstract of the disclosure, the invention is directed to a stake extracting arrangement having gas generating media for operating a piston in a vertically oriented cylinder, with the lower end of the piston rod carrying a lifting hook arrangement for engaging a stake to be extracted. Preferably, a number of lift and lock devices are provided on respective support legs which are connected with a cylinder support plate and a spider, such that the lifting hook arrangement may be prepositioned vertically prior to operation.

STAKE EXTRACTING APPARATUS

The invention described herein may be manufactured, used, and licensed by or for the Government for governmental purposes without payment to me of any royalty thereon.

The invention is related to stake extraction apparatus and, more particularly to stake extracting equipment particularly adapted for facilitated removal of stakes that have been in frozen earth, heavy clay, black asphalt, or the like for securely mounting heavy weapons, etc.

One of the objects of the invention is to provide stake removal apparatus having an adjustment mechanism by which the initial position of the lifting hook arrangement can be selectively chosen for desired stake engagement.

Another object of the invention is to provide such a stake removal apparatus which is of sturdy construction.

A further object of the invention is to provide such apparatus which in operation enables automatic release of an extracted stake.

These and other objects, features and advantages will become apparent from the following specification and accompanying drawings in which:

FIG. 1 is a partial sectional elevation view of a stake extracting arrangement embodying the principles of the invention.

FIG. 2 is a top plan view of the FIG. 1 structure.

As seen in FIG. 1, the stake 10 to be extracted, upon completion of its securing function for a weapon mount at a desired location upon most any form of ground, terrain or even frozen earth 11, is surrounded by a bottom plate 12 of the supporting structure portion of the stake extracting apparatus, the bottom plate or ring 12 being appropriately apertured to receive a plurality (preferably 3) of upstanding support legs 13. Each support leg 13 has a foot member 14 and stop plate 15 which are held in substantial abutment with each other by retaining rings or snap ring stops 16, 17 seated in vertically spaced peripheral grooves provided in the respective leg 13. At the upper end of each standard 13 a similar retaining ring 18 provides an upper limit stop for the suitable apertured cylinder plate 19 which is slidably adjusted to desired positions on standards 13 by respective lift and lock arrangements adjustable mounted thereon as will be hereinafter described and one of which being shown generally at 20. The cylinder plate 19 is centrally apertured and threaded for mounting the threaded lower end of vertical cylinder 21 housing sealed piston head 22 whose dependent rod 23 is slidably received by the cylinder plate O-ring 24 and backup ring 25.

The lower end of the piston rod 23 has lifting hook stop means 26 threaded thereto and slidably carries a lifting hook arrangement support 27 which overlies the stop means 26 and is appropriately slotted adjacent each of a plurality (preferably 3) of horizontally disposed pins 28 that correspondingly journal the apertured ear 29 of a respective pivotable lifting hook 30. The main body portion 31 of each lifting hook is offset outwardly of its pivot pin 28 so that the hook center of gravity will normally bias the hook inwardly, and the lower or hook portion 32 has an inclined flanged surface 33 to facilitate a grapnel engagement with a selected further inclined undersurface 34, 34 on preformed peripheral flanges of stake 10.

Stem valve 35 has its housing threadedly secured in an enlarged tapped approach or entrance 36 of a horizontal passage 37 in cylinder plate 19 that is in fluid communication with the underside of piston head 22. The forwardmost reduced portion of the stem valve housing has a plurality of radial openings 38, 38 that intersect its central bore 39 to permit delivery of generated pressure gas from aligned vertical passages 40 and 41 in the cylinder plate and sealed adapter 42 suitably threaded thereto. The adapter 42 is appropriately fluid connected to a gas generating or cartridge chamber within a rifle firing mechanism or action 43 whose stock has been omitted or removed and whose barrel has been replaced by the adapter 42. The rifle operating trigger 44, protected by guard 45, through an appropriate internal mechanism initiates a cartridge delivered to the cartridge chamber by a suitable

feed mechanism as actuated by bolt handle 46. Valve stem 50, adjustably connected to the valve housing internal threads 51, has a reduced forward end 52 terminating in a concavely recessed tip for holding steel ball 53 against its seat in the valve housing at the rearward end of passage 39 during generated gas delivery to the piston 22. By counterclockwise rotation of valve handle 55 the stem 50 can be withdrawn to the extent permitted by stem collar 56 and bleeder stem stop 57 carried by the valve housing, whereupon ball 53 may be unseated to allow post-operational exhausting of pressure gas through passage 39, passageway 60 within the valve housing and surrounding the reduced stem portion 52, and exit port 61 provided in the valve housing.

15 A spider support guide 64, normally overlying lifting hook support 27, has a central opening 65 to slidably receive the piston rod 23, as well as corresponding openings 66, 66 for slidable positioning along the support legs 13.

Upon an abrupt termination of upward piston rod travel upon reaching a sufficiently compressed fluid at the upper end 20 of cylinder 21, as well as the lifting hooks 30 whose upper flanges 70 have been physically raised by the lifting hook stop 26, the extracted stake will be tossed upwardly off the hook inclined surfaces 33, the lower surface of each hook portion 32 being cammed outwardly by the upwardly facing flange surface 71 of the released stake peripheral groove, and the lifting hooks 30 are thus freed to be thrown outward by their moments of inertia about their pivots for completely releasing the stake. The compressed fluid above the piston is vented to the atmosphere through vents 68, 68 (FIGS. 1, 2) in the cylinder cap 69 which is threadedly secured to the cylinder 21.

25 A pair of sturdy handle members 75, 75 (FIG. 2) are welded to the cylinder plate 19 in such a manner as to be substantially clear of the firing mechanism 43. The handles 75 are used in transporting the entire apparatus to predetermined stake locations, and they are convenient in raising the cylinder plate and associated structures to a selected elevation whereby the hook portions 32 may initially enter a stake groove.

30 By means of a pair of bolts or securing mechanism (not shown) on either side of each support leg 13 as indicated by 3 pairs of securing screws 78, 78 (FIG. 2) a jack housing 80 having upper and lower bifurcated ear portions 81, 82 is held integral with the cylinder plate 19. Each housing 80 has its ears 81, 82 apertured so as to be slidably mounted upon its respective support leg 13 and contains a corresponding lift and lock arrangement 20 by virtue of which the cylinder plate 19 and its associated parts may all be vertically adjusted relative to the support legs. Each lower ear 82 supports a compression spring 83 that surrounds its support leg 13 and in turn supports a tiltably mounted first lock member 84. A second tiltably mounted lock member 85 surrounds the leg 13 and is adapted to engage a dependent portion 86 of the upper ear portion 81.

35 Member 85 integrally carries a substantially horizontally extending first pivot post 87 upon which is journaled an intermediate link 88. Link 88 integrally carries a horizontal second pivot pin or post 89 and a lift and lock or jack handle or cam lever 90 has its forward end 91 journaled upon the second pivot pin 89 and provided with a concavely recessed in its upper surface to normally accommodate the convex lower contour of link 88. With the handle 90 held free and spring 83 normally under a predetermined amount of compression, the spring 83 will maintain the first lock member 84 in an unlocked and untilted slidable condition while urging it upwards into contact with the rolling contact lower surface of jack handle forward end 91. In this condition of the lift and lock arrangement, the second or upper lock member 85 is tilted in a locking position. When handle 90 is depressed in a clockwise direction (FIG. 1) about its pivot 89, it will roll along and

40 depress or tilt the first lock member 84 to a locking position, and its forward end 91 will engage and move link 88 and the pivot post 87 clockwise with handle 90 about pivot 89, thus freeing second lock member 85 and urging it and its associated parts upwardly to elevate cylinder plate 19 and its associated structures. Upon release of handle 90, it and the in-

termediate link 88 will return to their relative positions, permitting the upper lock member 85 to return to a locking condition, and by virtue of which the first or lower lock member 84 will be freed for upward movement as urged by spring 83. Repeated operation of the lift and lock devices 20 will provide the desired cylinder plate position, as permitted by the effectiveness of springs 83, such that the lifting hook arrangement will have capably secured the stake 10 thereto, prior to actuation of piston elevating trigger 44.

Various modifications, changes or alterations may be resorted to without departing from the scope of the invention as defined in the appended claims.

I claim:

1. In a stake extracting apparatus having an elongated vertical cylinder and a sealed piston slidably mounted therein: a cylinder plate having a central aperture for receiving and supporting said cylinder; a plurality of support legs each having an upper end portion slidably received by said cylinder plate; a piston rod having an upper end secured to said piston and a lower end carrying a lifting hook arrangement; a spider member having a plurality of openings and receiving each of said piston rod and support legs, said spider guiding said piston rod and lifting hook arrangement; a lift and dock device on at least one of said support legs engaging said cylinder plate; and gas generating means on said cylinder plate and in fluid communication with said piston head, so constructed and arranged that vertical adjustment of said lift and lock device will enable prepositioning said lifting hook arrangement to a predetermined initial location relative to said support legs.
2. The apparatus in accordance with claim 1 wherein said lift and lock device includes a housing having bifurcated and

apertured ear portions unitarily slidable upon its support leg, a compression spring resting on one of said ear portions and supporting a tiltably mounted first lock member, a second tiltably mounted lock member adapted to engage the other of said ear portions, a substantially horizontally extending first pivot post carried by said second lock member, a link having one portion journaled upon said first pivot post and carrying a second pivot post, and a cam lever having one end journaled upon said second pivot post and adapted to engage said first lock member and said link.

3. The structure in accordance with claim 1 in which said lifting hook arrangement comprises a lifting hook support member slidably mounted upon said piston rod below but adjacent said spider member and having a plurality of horizontally disposed pivot pins, a lifting hook pivotally mounted upon each pivot pin, each hook having an inner surface provided with an elongated recess defining vertically spaced upper and lower flange portions, said lower flange portion of each hook being defined by an inclined hooking surface for engaging a stake to be extracted, and a lifting hook stop member secured to said piston rod lower end and adapted to engage said upper flange portions.

4. The structure of claim 1 wherein said gas generating means comprises a rifle having a gas generating delivery passage and mounted on said cylinder plate, a passageway in said cylinder plate in fluid communication with the undersurface of said piston, and a bleeder valve secured to said cylinder seating against said passageway, said body having a longitudinal central passage in fluid communication with said passageway, radial port means communicating said central passage with said gas generating delivery passage, and an exhaust port for placing said central passage in fluid communication with an external environment.
